UNITED STATES PATENT OFFICE

BERTRAND A. PARKES, OF PHILADELPHIA, PENNSYLVANIA

DRYING MACHINE

Application filed May 18, 1929. Serial No. 364,084.

My invention relates to a new and useful drying machine and it relates more particularly to a drying machine using heated air as a drying medium, whereby any desired material such as piece goods, yarns, woolen or cotton stock and similar materials may be efficiently and economically dried by one and the same machine.

My invention further relates to a drying machine wherein the heated dry air is blown through the fabric, stock or other material being dried to insure the complete, thorough and quick drying of such fabric, stock or material by a single operation or passage through the drying machine.

My invention still further relates to a drying machine of this general character which is particularly adapted for drying delicate fabrics such as silks, rayons, chiffons and the like whereby such fabrics are dried free of wrinkles and creases and the markings necessarily resulting from such creases and wrinkles.

My invention still further relates to a drying machine wherein the heated air is constantly circulated and reheated to enhance its absorbing capacity and wherein the moist air is slowly and gradually expelled and replaced by fresh air so that no interference with the circulation of the air, or any sudden cooling thereof can take place.

My invention still further relates to a machine of this character wherein the material being dried may be propelled at any desired speed in accordance with the nature of and the amount of humidity in said material.

My invention still further relates to a drying machine of this character which is of a simple construction, inexpensive to produce and simple to operate.

To the above ends my invention consists of a housing, a series of heating coils in the lower portion thereof, a cylindrical fan above said coils, larger and smaller sprocket wheels at either end of said fan, sprocket chains carried by said sprocket wheels in spaced relation to each other, endless aprons carried by said sprocket chains, and means for propelling said chains and said aprons, the material

being dried being carried and confined between said aprons.

My invention further consists in providing novel means for controlling the circulation and replacement of the air heated by the heating coils, and in providing means for regulating and controlling the speed at which the sprocket chains and aprons carried thereby are propelled.

My invention still further consists of various other novel features of construction and advantage all as hereinafter described and claimed.

In the accompanying drawings:

Figure 1, represents a side elevation of a drying machine, embodying my invention, certain parts being removed to show the interior construction.

Figure 2, represents a section on line 2—2 of Figure 1.

Figure 3, represents a plan view of Fig. 1.

Figure 4, represents a view similar to Figure 1 showing a modified form of my invention.

Referring to the drawings, in which like reference characters indicate like parts, designates a drying machine embodying my invention, suitably supported on a frame or housing 2, and having the bottom or base 3 and the top 4. 8 designates a lower partition which divides the machine casing into an upper compartment 9 and a lower compartment 10, which compartments intercommunicate through the end ducts 11 and side ducts 12 in a manner and for a purpose hereinafter more fully set forth.

14 designates a series of heating coils disposed in the lower compartment 10 and supplied with steam or any other suitable heating medium in any suitable manner. The lower compartment 10 is provided with a fresh air inlet 15 while the upper compartment 9 is provided with the moist air outlet 16, said outlet and inlet serving to control the circulation of air and being hereinafter further referred to.

To the frame 2 of the machine, are secured the bearings 18 in which is journalled the shaft 19 which carries at one end thereof the

driving pulley 20 driven by any source of power not shown.

The shaft 19 carries and revolves the fan wheel 22 which is provided with the inclined vanes or blades 23 along its circumferential periphery. At either end of the fan wheel 22 is a sprocket rim 27 which carries the cross bars 24 which serve as baffle plates to distribute the air blown by the fan wheel 22. The sprocket rims 27 are carried by the sprocket wheels 28 and are secured thereto by the spacing blocks 26. The sprocket wheels 28 have the hubs 29 which are loose on the bearings 32 so that the sprocket wheels 28 are free to revolve independently of the shaft 19 as will be understood from Figure 2. 30 designates cross bars at either side of the machine which carry the bearings 31 in which are journalled the shafts 33 which carry the loose sprocket wheels 34 over which pass the endless sprocket chains 35 which also pass over and engage the sprocket rims 27 carried by the loose sprocket wheels 28. The sprocket chains 35 also pass over the loose sprocket wheels 38 on the shaft 39 and over the sprocket wheels 38^x fast on the shaft 40, the shafts 39 and 40 being journalled in the bearings 41 carried by the cross bars 30. The shaft 40 also carries the fast pulley 45 over which passes the belt 46 which also passes over the fast pulley 47 on the shaft 19 whereby the sprocket wheels 38^x are revolved to drive the sprocket chains 35. The chains 35 are connected by cross bars 49^x on the underside of which is the wire cloth or other flexible apron 50^x which forms an endless inverted conveyor which will be hereinafter referred to. 48 designates endless sprocket chains which pass over loose sprockets 42 on the shafts 43 and over the sprocket wheel 28. The endless sprocket chains 48 are connected by the transverse bars 49 which support the cloth or wire netting apron 50 to form an endless conveyor for carrying the stock 61 hereinafter further referred to (see Figs. 1, 2 and 3). The endless chains 48 ride over the inclined tracks 51 and the bottom horizontal tracks 52 as well as over the loose idle sprocket wheels 53 carried by the supports 54 and the loose idle sprocket wheels 55 carried by the frame 2 of the machine as will be understood from Fig. 1.

To prevent the air sucked from the heating compartment 10 through the ducts 12 from escaping, I provide the shields 94 which have the flanges 95 which register with the cylindrical members 93 carried by and revolving with the sprocket wheels 28. To prevent the air thus sucked and guided into the fan wheel 22 from being blown out except between the baffle plates 24 and through the aprons 50 and 50^x carried by the sprocket chains 48 and 35, I provide the shields 96 which extend from the flanges 95 of the shields 94 to the peripheries of the juxtaposed sprocket wheels 28 as will be best understood from Fig. 2. 97 designates a guard positioned between the sprocket chains 48 and 35 to prevent the scattering of the stock 61 and will be hereinafter referred to. In order to insure complete removal of the stock 61 from between the aprons 50 and 50^x, the latter is provided with the longitudinal blade 64 which is of a width or height substantially equal to the distance or space between said aprons, and which serves to remove the stock 61 from off the lower apron 50 as will be understood from Fig. 1 it being noted that any desired number of blades 64 may be employed if so desired.

The operation is as follows:—

The stock 61, such as wool, cotton, pulp or the like, is fed, automatically or manually onto the apron 50 carried by the chains 48 which travel in the direction of the arrow 60. When the apron 50 and chains 48 reach the idle rollers 42 on the shafts 43 at the left hand side of Figure 1, the stock 61 becomes confined between it and the apron or conveyor 50^x carried by the chains 35 passing over the idle sprockets 34 on the shaft 33 at the left hand portion of Figure 1 and travelling in the direction of the arrow 62, over the idle sprocket 38 on the shaft 39. The shield 97 serves to prevent the stock 61 from falling out laterally from between the aprons 50 and 50^x, as will be understood from Fig. 2. After leaving the idle sprockets 42 and 38 on the shafts 43 and 39 respectively, the chains 35 and 48 carrying the aprons 50^x and 50 respectively, then engage the outer sprocket wheel 28 and the inner sprocket rim 27 carried thereby with the stock 61 confined therebetween as will be understood from Fig. 1. In this position of the parts, and until the stock 61 has travelled completely around the sprocket wheels 28 and 27, the fan wheel 22 blows a constant current of hot air therethrough, said air being forced through the stock 61 by its inability to escape otherwise due to the provision of the shields or guards 94, 95 and 96 hereinabove referred to. After the stock 61 has travelled completely around the sprocket wheel 28, the chains 48 carrying the apron 50 which carries the stock pass over the idle sprockets 42 on the shafts 43 at the right hand side of Fig. 1, over the inclined tracks 51 and over the idle sprockets 53 on the right hand side of Fig. 1, where the stock 61 falls off the apron 50 carried by the chains 48, as at 63. The sprocket chains 48 then pass under the idle sprockets 55 on the lower right hand side of Fig. 1, over the bottom tracks 52, under the sprockets 55 at the lower left hand side of Fig. 1 and over the sprockets 53 at the left hand side of Fig. 1 to the inclined tracks 51 where the stock 61 is again fed onto the apron 50 carried thereby and the cycle of operations begins over again. The motive power for the propulsion of the stock 61 and

the aprons 50 and 50^x carried by the chains 48 and 35 is provided by the belt 46 which passes over the pulley 47 fast on the revolving shaft 19 and over the pulley 45 carried by the shaft 39 which also carries fast the sprocket wheels 38^x over which chains 35 pass as will be understood from Fig. 1.

The air sucked into the fan wheel 22 through the ducts 12 and blown through the aprons 50 and 50^x carried by the sprocket chains 48 and 35 around the sprocket wheels 28 and 27 and through the stock 61, flows downwardly through the end ducts 11 back into the heating chamber 10 to be dehydrated and again sucked through the side ducts 12 into fan wheel 22. This is accomplished partly due to the fact that moist air leaving the stock 61 is heavier than dry air and partly due to the fact that constant suction of the air by the fan wheel 22 from the lower compartment 10 through the side ducts 11, reduces the pressure in said lower compartment, thus creating a downward current through the end ducts 11. A part of the moist air in the compartment 9 escapes through the outlet 16, thereby causing a draft of fresh air to flow into the compartment 10 through the inlet 15. In this way the air in the compartments 9 and 10 is changed or replenished gradually, so that no sudden cooling of the air supply takes place as would be the case if the air in said compartments were to be completely changed or replaced at stated intervals.

In Figure 4 I have shown my novel drying machine particularly adapted for drying a fabric 70 such as silk, piece goods, chiffon, rayon or other delicate material.

In this construction I only add the feed roll 71 carried by the shaft 72 and the feed roll 73 carried by the shaft 74 and meshing with or frictionally driven by the roll 75 on the shaft 76 which also carries the pulley 77 over which passes the belt 78 which also passes over the pulley 79 carried by the shaft 80 which also carries idle sprocket wheels 81 (corresponding to the sprocket wheels 53 at the left hand portion of Figure 1), over which travel the sprocket chains 48. The cloth 70 passes over the roll 71, under the roll 73 and over the roll 75 before entering the space between the aprons 50^x and 50 carried by the sprocket chains 35 and 48 as indicated by the arrow 82. By regulating the speed of rotation of the roll 75, the speed at which the cloth 70 is fed or propelled can be controlled to synchronize with the speed of the sprocket chains 48 and 35 travelling over the sprocket wheels 28 and the sprocket rims 27 carried thereby. At the outlet end 80 of the machine I provide a take up roll 84 over which the dried cloth 70 passes before reaching the truck or other receptacle 85. The roll 84 is carried by a shaft 86 which also carries the pulley 87 over which passes the belt 88 which also passes over the pulley 89 on

the shaft 90 which carries the idle sprockets 91 (corresponding to the idle sprockets 53 at the right hand portion of Fig. 1) whereby the speed at which the cloth 70 is drawn out of the machine may be controlled and regulated in synchronism with the speed of the feed roll 75 and the speed of the sprocket wheels 27 and 28.

By regulating the speed of feed and take up rolls 75 and 84, the cloth 70 is prevented from contacting with the sprocket chains 48 and the apron 50 carried thereby by making the length of the cloth 70 found at any one time between the aprons 50 and 50^x carried by the sprocket chains 48 and 35 slightly less than the circumference of the outer sprocket wheels 28. The cloth 70 is also prevented from contacting with the apron 50^x carried by the sprocket chains 35 by the blast of hot air which is blown through the cloth 70 by the fan wheel 22 which tends to maintain the cloth 70 drawn taut as will be understood from Figure 4. By this novel arrangement the cloth 70 is dried free of wrinkles, creases or markings since it is protected from all contact with solid objects while it is in the moist condition. In other words while the delicate fabric 70 is being dried it is practically suspended in a stream of hot air with no physical contacts whatsoever. The advantage of this method over the heretofore prevailing method of suspending the cloth 70 from transverse rods or poles in loops, is obvious since by this latter practice the cloth 70 carried what is known as "stick markings", was liable to get wrinkled and was only superficially subjected to hot air instead of having a blast of hot air passing through it. In fact the force of the air blowing through the cloth 70 is sufficient to smoothen out any wrinkles or creases that may exist in the cloth before reaching the sprocket wheel 27.

While I have shown in the accompanying drawings, a single drying machine, it is to be understood that it is within the scope of my invention to provide a series of sprocket wheels 27 and 28, over which will pass a continuous pair of sprocket chains 48, there being a corresponding series of sprockets 34, 38, 38^x and 42, with sprocket chains 35 passing thereover for each pair of sprocket wheels 27 and 28 so that the stock 61 or cloth 70 being dried may pass over a series of fan wheels 22 and be dried in successive stages. Furthermore, it is within the scope of my invention to arrange the series of sprocket wheels 27 and 28 and their adjuncts that the cloth or stock 61 or 70 may not only be dried in successive stages, but that it may, after having been thoroughly dried, be slightly humidified to prevent the "cracking" or other damage that might result to the fiber of the material being dried from excessive dehydration.

It will further be apparent that while I have shown my novel drying machine adapt-

ed for the purpose of drying stock, such as cotton, wool, or pulp, etc., and for the purpose of drying cloth such as rayon or chiffon, etc., it is within the scope of my invention 5 by effecting various slight changes which are not a part of the invention, to adapt my novel drying machine for the purpose of drying any desired material.

Having thus described my invention what 10 I claim is new and desire to secure by Letters Patent is:—

1. In a device of the character stated, a housing, a fan wheel rotatably carried thereby, a pair of sprocket wheels at each end of 15 said fan wheel, said pairs of sprocket wheels being revoluble, independently of said fan wheel, endless sprocket chains engaging said sprocket wheels, endless aprons carried by said sprocket chains, means for revolving said 20 fan wheel, and means for actuating said sprocket chains to propel said aprons around said fan wheel.

2. In a device of the character stated, a housing, a fan wheel rotatably carried thereby, sprocket wheels of different diameters 25 at each end of said fan wheel, said sprocket wheels being revoluble independently of said fan wheel, endless sprocket chains travelling over said sprocket wheels, endless aprons carried by said sprocket chains, means for revolving said fan wheel, means for actuating said 30 sprocket chains to propel said aprons around said fan wheel, and means for regulating the speed of said aprons independently of the 35 speed of said fan wheel.

3. In a drying machine of the character stated, a housing, a fan wheel rotatably carried thereby, sprocket wheels of different diameters rigidly secured in spaced relation to 40 each other at each end of said fan wheel and revoluble independently of said fan wheel, endless sprocket chains travelling over said sprocket wheels, endless aprons carried by said sprocket chains in spaced relation to 45 each other, said aprons being adapted to receive the material to be dried therebetween, means for revolving said fan wheel and means for actuating one of said sprocket chains, to 50 propel said aprons around said fan wheel in spaced concentric relation to each other.

4. In a drying machine of the character stated, a housing, a fan wheel rotatably carried thereby, sprocket wheels rigidly secured together at each end of said fan wheel and 55 rotatable independently of said fan wheel, sprocket chains engaging said sprocket wheels, endless aprons carried by said sprocket chains in spaced relation to each other and adapted to receive the material to be dried 60 therebetween, means for revolving said fan wheel, means for actuating one of said sprocket chains to propel said aprons around said fan wheel in concentric relation to each other, and end guards disposed between the 65 peripheries of said aprons for preventing the

lateral falling out of the material carried between said aprons during the travel of the latter around said fan wheel.

5. In a drying machine of the character stated, a housing, a fan wheel rotatably carried thereby, sprocket wheels of different diameters secured together at each end of said fan wheel and rotatable independently of said fan wheel, concentric sprocket chains engaging said sprocket wheels, endless 70 aprons carried by said chains in spaced concentric relation to each other, means for propelling said aprons around said sprocket wheels, and closures at either end of said fan wheel for forcing the air blown by the latter through said aprons.

6. In a drying machine of the character stated, a housing comprising a heating compartment and a drying compartment, a heating element in said heating compartment, a fan wheel in said drying compartment, means for revolving said fan wheel, air ducts leading from said heating compartment into said fan wheel, air ducts leading from said drying compartment back into said heating 90 compartment, means for revolving the material to be dried around said fan wheel, an air outlet in said drying compartment and an air inlet in said heating compartment.

7. In a device of the character stated, a housing, a fan wheel rotatably mounted therein, a sprocket wheel at each end of said fan wheel rotatable independently of the latter, a sprocket rim of a slightly lesser diameter than, and carried rigidly by each of said sprocket wheels, baffle plates carried by said sprocket rims in proximity to the periphery of said fan wheel adapted to deflect the air blown by said fan wheel, endless sprocket chains engaging said sprocket wheels and 95 rims, endless aprons carried by said sprocket chains adapted to travel around said fan wheel in spaced relation to each other and to receive the material to be dried therebetween, and means for propelling said aprons around 100 said fan wheel independently of the rotation of the latter.

8. In a device of the character stated, a housing, a fan wheel rotatably mounted therein, sprocket wheels at each end of said fan wheel, endless sprocket chains engaging said sprocket wheels, means for propelling said chains, endless aprons carried by said chains adapted to be propelled around said fan wheel in spaced concentric relation to 115 each other, and to receive the material to be dried therebetween, and means carried by one of said aprons adapted to coat with the juxtaposed operative surface of the other of said aprons for removing the material being dried from said last mentioned apron after a complete revolution of said aprons around said fan wheel.

9. In a device of the character stated, a housing, a fan wheel rotatably mounted 120

therein, means for driving the latter, idle inner and outer sprocket wheels mounted in said housing at each end of said fan wheel, said inner and outer sprocket wheels being rigidly secured together and rotatable as a unit independently of said fan wheel, endless inner sprocket chains engaging said inner sprocket wheels, endless outer sprocket chains engaging said outer sprocket wheels, endless aprons carried by said inner and outer sprocket chains and adapted to travel around said fan wheel in spaced concentric relation to each other, and means for propelling said inner sprocket chains independently of the rotation of said fan wheel.

15 10. In a drying machine of the character stated, a housing, a fan wheel rotatably carried thereby, means for revolving said fan wheel, sprocket wheels carried by said housing in operative relation to said fan wheel, endless sprocket chains engaging said sprocket wheels, means for propelling said sprocket chains endless aprons carried by said sprocket chains adapted to travel around said fan wheel in spaced relation to each other to receive the material to be dried therebetween, means for feeding said material into the space between said aprons and means for withdrawing said aprons after a complete revolution of said material around said fan wheel.

20 25 30 35 40 11. In a device of the character stated, a housing, a fan wheel rotatably carried thereby, sprocket wheels at each end of said fan wheel, said sprocket wheels being revoluble independently of said fan wheel, endless sprocket chains engaging said sprocket wheels, endless aprons carried by said sprocket chains, means for revolving said fan wheel, means for actuating said sprocket chains to propel said aprons around said fan wheel.

BERTRAND A. PARKES.
